(57) **CLAIM**

The ornamental design for a wastebasket, as shown.

DESCRIPTION

FIG. 1 is a perspective view of a wastebasket showing my new design;

FIG. 2 is a front view thereof;

FIG. 3 is a rear view thereof;

FIG. 4 is a side view thereof;

FIG. 5 is a top view thereof; and,

FIG. 6 is a bottom view thereof.

The broken line(s) in FIG. 6 which define the bounds of the claimed design form no part thereof.
